UNITED STATES PATENT OFFICE.

ARTHUR W. WADSWORTH AND ARTHUR P. CONANT, OF FORT THOMAS, KENTUCKY,
ASSIGNORS TO THE WADSWORTH WATCH CASE COMPANY, OF DAYTON, KENTUCKY,
A CORPORATION OF KENTUCKY.

HOLDING MEANS FOR DETACHABLE STRAPS.

Application filed August 3, 1923. Serial No. 655,498.

To all whom it may concern:

Be it known that we, ARTHUR W. WADSWORTH and ARTHUR P. CONANT, citizens of the United States, residing at Fort Thomas, 5 in the county of Campbell and State of Kentucky, have invented certain new and useful Improvements in Holding Means for Detachable Straps, of which the following is a specification.

10 Our invention relates to lugs for wrist or strap-watches and buckles.

The object of our invention is to provide simple, compact, economical, efficient, strong and easily attachable and detachable means 15 for securing a strap to a wrist or strap-watch or buckle and to so construct and arrange said means as to be substantially concealed or invisible when in use.

Our invention consists in providing a 20 watch-case or buckle with a substantially T-shaped lug adapted to be inserted through a slot into a loop on the end of the strap whereby the strap is detachably secured to said watch or buckle, as the case may be.

25 Our invention also consists in the construction, combination and arrangement of the lug and of the strap as herein set forth and claimed.

In the drawing:

30 Fig. 1 is a plan view of a wrist watch and strap embodying our invention;

Fig. 2 is a view of the under side thereof;

Fig. 3 is a section of the watchcase and strap holding lugs;

35 Fig. 4 is a view of the under side of the loop end of the strap;

Fig. 5 is a front view of a watchcase embodying our invention showing the strap dotted at the right side and the upper part 40 of the loop broken away on the left side;

Fig. 6 is a plan view showing our invention applied to another form of watchcase;

Fig. 7 is an edge view thereof;

Fig. 8 is an end view thereof;

45 Fig. 9 is a side view of one of the lugs;

Fig. 10 is a rear view of said lug;

Fig. 11 is a plan view of a buckle having our lug applied thereto; and

50 Fig. 12 is a side view thereof with the looped end of the strap in section.

In the embodiment of our invention as illustrated and which shows preferred constructions we provide a substantially T-shaped lug which is constructed of substan-

tially the shape shown in Figs. 9 and 10. 55 As shown, said lug is provided with a strap holding head or bar 1 having curved edge 2 and straight edge 3 forming curved or tapered ends 4. Said head or bar is supported and spaced apart from the watchcase 5 or 60 buckle 6, as the case may be, by base 7 connected to supporting stem 8 which fits into a socket or opening 9 in the watchcase or buckle to which it is secured by riveting, soldering or otherwise, as desired, or if preferred it may be formed integral therewith as shown in Figs. 11 and 12. The shoulder 10 at the junction of the base and stem serves to firmly brace and support the stem and to hold the head in fixed spaced apart relation 70 from the watchcase or buckle thereby forming spaces 11 between the head or watchcase and buckle to receive the looped end 12 of strap 13 therebetween. The flat side 3 of the T bar 1 is spaced from the watchcase or 75 buckle preferably a distance substantially equal to the thickness of the material comprising one ply of the belt thereby permitting the looped end 12 to completely fill the spaces 11 and concealing the lug. The strap 80 is formed by folding a strip of leather or other equivalent material upon itself and sewing the edges 14 together except at the looped end 12. Said strap is provided upon its under ply 15 adjacent the looped end 85 with a longitudinal slot 16 through which the head 1 is inserted into holding position in the loop. The slot 16 is preferably cut away or enlarged at 16' adjacent the loop 12 to receive the base 7 and to provide for 90 a neat, snug and compact fit and arrangement of the parts relative to each other and to the watchcase or buckle. It also provides for more ready insertion than otherwise, of the head into the loop. The base is also 95 preferably formed at an angle to the edge of the watchcase or buckle to which it is attached in order that the looped end of the strap and the top of the watchcase or buckle will be substantially flush and assist in forming part of the curve or circle of the strap around the wrist or other member to which it may be secured. A closer and neater fit is thus obtained and the base is completely 100 covered thereby entirely concealing the strap attaching means when in position upon the wrist or other member to which it is attached.

When the parts are thus constructed the operation of attaching and detaching when desired is very simple and convenient. To attach merely place the head longitudinally 5 of the slot, insert one end thereof beneath the end of the slot until the base engages the end thereof, then give the base a quarter turn whereby the other end of the head passes beneath the lower ply of the strap 10 when the head may be drawn into the loop ready for use. To detach merely reverse the operation.

While we have shown and described particular constructions and arrangements it 15 will be understood that modifications thereof for the purposes intended may be made without departure from the scope or spirit of the invention as defined in the claims.

What we claim as new and desire to set 20 cure by Letters Patent is:

1. In detachable holding means, a T-lug suitably mounted and spaced apart from the article to which it is attached, and a looped strap having a slot therein whereby said lug 25 may be detachably connected to said loop.

2. In detachable holding means, a T-lug suitably mounted and spaced apart from the article to which it is attached, and a looped strap having a longitudinal slot extending 30 from the loop longitudinally of the strap, substantially as set forth and for the purposes specified.

3. In combination with a watchcase or buckle, detachable holding means comprising a transverse bar spaced apart from and supported by said watchcase or buckle, and a strap having a loop and adjacent slot whereby said bar may be inserted into said 35 loop or detached therefrom, when desire

4. In detachable holding means, a lug 40 comprising a transverse bar, a base and stem, means for securing said stem to an object with said bar in spaced apart relation from said object, a strap having a loop in one end and having a slot in its under side, extending from the looped end sufficiently to permit the insertion of said bar therethrough into said loop.

5. In detachable holding means, a lug 50 suitably mounted and having a cross-bar curved upon one edge and straight upon its inner edge and spaced apart from the object to which it is attached, and a strap having a slot and loop to detachably receive said lug.

6. In combination with a watchcase or buckle, a lug having a cross-bar and having a shank thereon secured to said watchcase or buckle at an angle thereto and a looped strap having means whereby said cross-bar 55 may be inserted into detachable holding engagement therewith.

7. A watchcase or buckle, a lug comprising a bar having tapered ends and a stem whereby said lug is secured to the watchcase or buckle in combination with a strap having a loop and slot whereby said lug and strap 60 may be detachably connected.

8. In a device of the class described, a lug comprising a shank having a stem, a cross-bar curved on its edge away from said stem and straight on its edge adjacent said stem and a base forming a connection between said cross-bar and stem and having a shoulder adjacent said stem, substantially as set forth and for the purposes specified.

ARTHUR W. WADSWORTH.
ARTHUR P. CONANT.
